(No Model.)

A. A. ACKERLY.
RAILWAY SWITCH.

No. 405,977.

Patented June 25, 1889.

UNITED STATES PATENT OFFICE.

AARON A. ACKERLY, OF CHICAGO, ILLINOIS.

RAILWAY-SWITCH.

SPECIFICATION forming part of Letters Patent No. 405,977, dated June 25, 1889.

Application filed October 17, 1888. Serial No. 288,398. (No model.)

To all whom it may concern:

Be it known that I, AARON A. ACKERLY, a citizen of the United States, residing at Chicago, in the county of Cook and State of Illinois, have invented a certain new and useful Improvement in Railway-Switches, which is fully set forth in the following specification, reference being had to the accompanying drawings, in which—

10 Figure 1 is a plan view of a construction embodying my invention; Fig. 2, a detail plan view of one of the bell-crank levers detached; Fig. 3, a similar view of a modified form of bell-crank lever; Fig. 4, a detail elevation of a portion of the same; Fig. 5, a sectional view taken on the line 1 1 of Fig. 4; Fig. 6, a detail elevation illustrating the safety device, and Fig. 7 a detail sectional view taken on the line 2 2 of Fig. 3.

20 Like letters refer to like parts in all the figures of the drawings.

My invention relates to railway-switches, and is in the nature of an improvement upon the construction set forth in an application 25 filed by me July 11, 1888, Serial No. 279,636.

The object of my present invention is to improve the construction and operation of the apparatus set forth in said prior application, so as to render the same more efficient and 30 safe.

To these ends my invention consists in certain novel features, which I will now proceed to describe, and will then particularly point out in the claims.

35 In the drawings, A and A' represent, respectively, the two rails or series of rails composing the main line, and B and B' the two rails or series of rails composing the branch line or siding. The switch-rails for connecting the main line with either of these lines are shown at C and C', said switch-rails being 40 free to move laterally in the manner usual in switches of this construction and being connected by means of tie-bars c.

45 The main-line rails A and siding-rails B' meet each other in pairs at the point where the track-crossing is located, and where in the ordinary construction a frog is employed to effect this crossing. In order to dispense with 50 this frog I make one of these pairs of rails laterally movable, and in the present instance

I have shown that pair as movable which is located farthest away from the switch. The movable main line A is continued to a point opposite the end of the fixed main line A', 55 while the movable siding-rail B' is beveled off at its end to fit against the side of the movable main-line rail, and is securely bolted or otherwise firmly connected thereto. The angle formed by the divergence of these rails is 60 occupied by a filling A² of wood or other suitable material, which not only serves to fill the said space, and thus prevent any one from having his foot caught in the said space, but also acts as a firm brace to hold the two movable rails in proper relative position at their free ends. The movable rail A is enabled to move laterally either through the elasticity of the rail itself or through a suitable loose connection at its end farthest away from the 65 track-crossing.

Since the rails A and B' diverge, there will naturally be a differential movement between them. This movement was accommodated in my prior application at the point where the 75 two rails meet; but as I deem a solid connection better at this point I have devised a construction whereby this movement is accommodated at the other end of the rail B'. To effect this result I connect the movable rail 80 B' to the abutting fixed rail B by means of fish-bars D, which are bolted to the end of the fixed rail B, and are connected to the end of the movable rail B' by means of bolts d, which pass through slots b in the said movable rail, as shown in Figs. 4 and 5. A sleeve or thimble d' is mounted on the bolt d between the fish-bars D, and serves to keep the said bars from frictional contact with the rail B', thus allowing the said rail longitudinal play with respect to the bars. This play is sufficient to allow for the differential movement of the two rails A and B', and in order to hold the rail B' more firmly in position suitable chairs E are employed at this joint. 90

F indicates the switch-stand, provided with a vertical rock-shaft F', having a handle-lever f, by means of which it may be operated. The construction and arrangement of this stand are substantially identical with that shown 100 and described in my prior application, and therefore need no detailed description here. A

connecting-rod f' serves to operate the crossing-rails A and B', as in my said former application, and a second connecting-rod f^2 leads from the switch-stand to a lever F^2 , pivoted on one of the ties. Another connecting-rod f^3 leads from the other end of said lever to a bell-crank lever F^3 , pivoted on one of the ties at the end of the switch-rails C and C', and the other end of said bell-crank lever F^3 is provided with a connecting-rod f^4 , which is connected to said switch-rails to operate them simultaneously with the crossing-rails, as in my said prior application.

G indicates the lock, and G' the hand-lever controlling the same, these parts and their various mechanisms being constructed as in my prior application hereinbefore referred to. A connecting-rod g , controlled by the lever G', leads from the switch-stand to a three-armed lever G^2 , to one arm of which it is connected. To another arm of the three-armed lever G^2 is pivoted a rod G^3 , which is connected to the lock G by means of a bell-crank g' and link g^2 . The other end of the rod G^3 is connected to a bell-crank lever G^4 .

H and H' represent safety-slides connected, respectively, to the siding-rail B and main line A', and extending from the switch-rails to the crossing-rails, or to a point in line with the crossing. These slides rest normally in such a position that their tops are on a level with or slightly below the tops of their respective rails. Each slide is provided with a laterally-projecting flange h , which may be either continuous or in sections, as shown, and with a series of downwardly-extending flanges h' . Each flange h' is provided with an inclined slot h^2 , through which passes a bolt or pin h^3 , secured to the rail. The slide H is connected to the third arm of the three-armed lever G^2 by means of a connecting-rod H^2 ; and the slide H' is similarly connected to the bell-crank lever G^4 by means of a connecting-rod H^3 . The purpose of these slides is as follows: Let it be supposed that a car or the wheels of a car have passed from the switch-rails C C' to the main rails A A'. If the switch be thrown before the said wheels reach and pass the crossing, it will be obvious that they will leave the track at this point. The connection of the slides H and H' with the handle-lever G', which operates the lock, is such, however, that when the handle-lever is thrown into position to open the lock and permit the switch to be turned the said slides project above the rails, and it will at once be seen that if any wheels are upon the rails A' or B the handle-lever G' cannot be turned to unlock the lock, and consequently the switch cannot be thrown so long as there are any wheels standing or moving upon the rails A' or B between the switch-rails and crossing.

In order to provide for the taking up of the wear which is likely to occur through the continuous usage of the mechanism just described, I provide means for this purpose, in connection with any or all of the various bell-crank

and other levers to which the connecting-rod is attached. As an illustration of this connection, take the bell-crank lever F^3 , which is shown in detail in Figs. 2 and 3 of the drawings. This bell-crank lever is pivoted at i , and the pivot i' , to which the connecting-rod f^3 is attached, is mounted eccentrically in a disk or roller I, which is in turn mounted in the bell-crank lever F^3 , and is capable of being rotated therein, being secured in any desired position by means of a set-screw i^2 . It will be observed that the disk or roller I may be turned so as to bring the pivot i' farther away from the pivot i , and thus practically increase the length of the lever, and thereby take up any wear which may occur. The pivot i^3 of the connecting-rod f^4 is similarly mounted in a disk I'.

In the construction shown in Fig. 3 of the drawings, the lever I' is provided at its ends with longitudinal slots j , in which are mounted blocks J, capable of sliding longitudinally therein, the said blocks carrying the pivots i^3 and i^4 , as in the construction just described. These blocks may, obviously, be moved farther from or nearer to the pivot i of the lever F^3 , and may be secured after adjustment by set-screws i^2 . It will be observed that a means is thus provided for varying the length of the various levers, and thereby taking up all wear which may occur in the connections, thus assuring a full throw of the switch and crossing rails at each movement of the operating-lever.

It is obvious that various modifications in the details of construction and arrangement of the parts may be made without departing from the principle of my invention, and I therefore do not wish to be understood as limiting myself strictly to the precise details hereinbefore described, and shown in the drawings.

Having thus described my invention, what I claim as new, and desire to secure by Letters Patent, is—

1. The combination, with the laterally-movable main rail A, of the laterally-movable siding-rail B', rigidly connected to said rail A at its front end, the fixed siding-rail B, the fish-plates D, and the bolts d, connecting said fish-plates and provided with sleeves or thimbles d' , said plates passing through suitable slots b in the movable rail B', substantially as and for the purposes specified.

2. The combination, with the laterally-movable crossing-rails A and B', rigidly connected at their meeting ends, of the filling A², of wood or other suitable material, secured in the angle between said rails, substantially as and for the purposes specified.

3. The combination, with the laterally-movable switch and crossing rails and their operating mechanism, of locking mechanism for securing the same in position, and guard-slides connected to the fixed main and siding rails between the switch and crossing rails and controlled by the locking mechanism,

substantially as and for the purposes specified.

4. The combination, with the lock G, link g^2 , and bell-crank g' , of the hand-lever G' , 5 connecting-rod g , three-armed lever G^2 , transverse rod G^3 , bell-crank lever G^4 , and the slides H and H' , connected, respectively, to the three-armed lever G^2 and bell-crank lever G^4 , substantially as and for the purposes 10 specified.

5. The combination, with the laterally-movable switch and crossing rails, of the switch-stand and its operating-lever, and suitable connecting-rods and intermediate levers, 15 the pivots whereby the connecting-rods are

connected to said levers being adjustable toward and from the fulcrum of the lever, substantially as and for the purposes specified.

6. The combination, with the laterally-movable switch-rails C and their operating-lever, of the connecting-rods, the intermediate lever F, provided with slots j , the blocks J, mounted in said slots and adjustable therein, securing devices for said blocks, and the pivots i' and i^3 , mounted in said blocks, substantially as and for the purposes specified. 20 25
